TWO-SPEED HYDRAULIC JACK

Edward P. Grime, Los Angeles, Calif.

Application September 23, 1946, Serial No. 698,648

1 Claim. (Cl. 60—52)

My invention relates to a hydraulic jack and more specifically to a two-speed jack. In the operation of hydraulic jacks, the original load on the jack is usually very light and if the fluid enters the main hoisting cylinder, it requires a great number of strokes to force this cylinder out.

It is, therefore, an object of my invention to provide a small auxiliary cylinder which will actuate the jack while the load is light and lift the piston in the main cylinder, but when the load passes a certain point, the fluid is automatically ported into the main cylinder to actuate the larger piston.

Other objects and advantages of my invention will be apparent from the following description and preferred embodiments thereof.

In the drawing:

Figure 1 is a longitudinal section of my hydraulic jack.

Figure 2 is a cross-section, taken on the line 2—2 of Figure 1.

A hydraulic jack constructed in accordance with the preferred embodiment of my invention comprises a housing 1, to which a cylinder 2 is threaded at 3. Carried in the cylinder 2 is a large piston 4, which has sealing devices 5 to close off a cylinder head 6. Carried by the piston 4 is a ram 7, which can have any of the usual attachments fastened to its head 8 to lift or move said attachments. The ram 7 has guide members 9 to keep the same centered in the cylinder 2. A cylinder 10 in the center of the ram 7 has there-in a sleeve 11, which is threaded at 12 to the housing 1.

Preferably formed at the opposite end of the housing 1 from the cylinder 2 is a cylinder 13, in which is positioned a piston 15, which has attached thereto a connecting shaft 16, which can be connected at 17 to a handle or other means for reciprocation.

A chamber 18 in the housing 1 provides a storage chamber for hydraulic fluid, such as oil. A bore 19 passes through the housing 1 and is closed at one end by a plug 20 and at the other end by a mechanism, to be hereinafter described. A bore 21 connects the end of the cylinder 13 with the bore 19 and passage 22 in the sleeve 11. A bore 23 connects the bore 21 with a port 24 entering the chamber 18. A ball valve 25 is positioned in the bore 21 to close off the bore 21 from the bore 19, while a ball valve 26 closes the bore 23 from the bore 21.

In the operation of my device, when the piston 15 is reciprocated in the cylinder 13 on its suction stroke, it lifts the ball 26 from its seat, open-

ing the bore 23 to the bore 21 and sucks oil from the chamber 18 into the cylinder 13. At the same time, this suction and any pressure in the passage 22 or the bore 19 forces the ball valve 25 closed. Upon the opposite stroke of the piston 15, the pressure forces the ball valve 26 closed and opens the valve 25, forcing the oil into the passage 22 and the cylinder head 10a, thus causing movement of the ram 7. I prefer to have the cylinders 10 and 13 of substantially the same diameter, thus one stroke of the piston 15 will move the ram 7 the same distance. When, however, the pressure upon the head 8 becomes so great that the pressure developed in the head 10a by the piston 15 can no longer be increased, the ball valve 27 is forced open and the oil then passes through the bore 19 into the cross port 28 into the main cylinder head 6, which then drives on the greatly expanded area of the piston 4, increasing the mechanical advantage upon the ram 7, thus automatically permitting the same size piston 15 to lift greater loads as the diameter of the cylinder 2 is substantially larger than the diameter of the cylinder 13. A spring 29 maintains the ball valve 27 closed until the load is high enough to require the extra mechanical advantage. In the preferred form of my invention, I have found that the spring 29 should not be compressible until a load of 500 pounds is placed upon the ball valve 27, which should be approximately a closure for a $\frac{1}{16}$ " diameter valve seat.

While the ram 7 is being actuated only by the pressure in the head 10a, a back pressure would result in the cylinder head 6. I therefore provide a port 30, communicating with the port 24 and the bore 19 and closed by a ball valve 31. As long as there is no pressure in the bore 19 below the valve 27, movement of the ram 7 moves the piston 4 outwardly and will suck open the ball valve 31, allowing hydraulic fluid to pass from the chamber 18 into the cylinder head 6, thus preventing any back pressure in the cylinder.

To allow my hydraulic jack to return to its original position, I provide a lever 33, which is pivoted at 34 to the housing 1 and contacts a push rod 35, which strikes a ball valve 36. When the lever 33 is depressed, it forces down the push rod 35, opening the ball valve 36, allowing the hydraulic fluid in the head 10a and the passage 22 to be ported through the bore 37 back to the chamber 18. A second push rod 38 is in contact with the ball valve 36 and the ball valve 27 and forcing open of the ball valve 36 causes the push rod 38 to push open the ball valve 27, per-

mitting the fluid in the cylinder head 6 to port out through the port 37 into the chamber 18. A spring 39 is positioned to act against the projection 40 and maintain the push rod 35 and the lever 33 in a normal position to allow the ball valves 36 and 27 to remain normally closed.

While I have described the preferred embodiments of my invention, I am not limited to any of the details herein set forth, except as described in the following claim:

I claim:

In a hydraulic jack, a body, a lifting piston slideable in a primary cylinder attached to said body, a secondary cylinder in said piston, a reciprocating piston pump in the said body having a pump cylinder substantially the diameter of said secondary cylinder, an enclosed source of hydraulic fluid, a port connecting said pump cylinder with said fluid supply closed by a check valve when said pump is compressing, a port connecting said pump cylinder with said primary cylinder closed by a check valve when said pump

is in its suction stroke, a port connecting said primary and said secondary cylinders and closed by a check valve until the pressure in said secondary cylinder rises to a predetermined point, a check valve normally held closed by the pressure in said secondary cylinder adapted to be opened by a push rod to bleed off the fluid from said secondary cylinder to said fluid supply, a push rod connecting said bleed off check valve and said check valve between said primary and said secondary cylinders.
